HANGER FOR TROUSERS AND SKIRTS

Filed March 18, 1947

UNITED STATES PATENT OFFICE

2,493,860

HANGER FOR TROUSERS AND SKIRTS

George C. Deck, Buffalo, N. Y.

Application March 18, 1947, Serial No. 735,420

5 Claims. (Cl. 223—96)

1

This invention relates to clothes hangers and more particularly to hangers for trousers and skirts.

It is an object of the present invention to provide in a hanger for trousers and skirts a hook element for suspending the hanger which serves as the means for effecting the tightening of the parallel retaining elements of the hanger, wherein the hook is merely brought to an upright position to effect the tightening of the parallel elements and to release the trousers or skirts the hook element is brought to a released or down position.

Other objects of the invention are to provide a clothes hanger for trousers and the like which is of simple construction, cheap to manufacture and easy to operate.

For other objects and for a better understanding of the invention, reference may be had to the following detailed description taken in connection with the accompanying drawing, in which

Fig. 1 is a side elevational view of one form of the invention.

Fig. 2 is an end elevational view of the form of the invention shown in Fig. 1.

Fig. 3 is an enlarged fragmentary view, in section, and illustrating the operation of the hook portion for effecting the locking of the parallel retaining elements.

Fig. 4 is a fragmentary view of a different hook arrangement wherein the hook need not be pivoted to such a great extent to effect the locking operation and wherein the hook will be maintained normally in both positions of adjustment in an upright position so that the hanger can be supported by the hook regardless of whether it has been locked or released.

Fig. 5 is a fragmentary side elevational view taken on line 5—5 of Fig. 4 and looking in the direction of the arrows thereof.

Referring now particularly to Figs. 1, 2 and 3, 10 and 11 represent parallel retaining elements between which the trousers or skirt are extended. Fitted into the upper edges of the parallel elements 10 and 11, are double wire portions 12 and 13, respectively. These portions can be formed of a strap or wire material which is bent to form adjacent portions connected together at their upper ends as indicated at 14. The portions 12 and 13 at their lower ends being connected to the parallel elements 10 and 11 as seen in Fig. 2. These wires are of spring material and will bend. If the parallel retaining elements 10 and 11 are made of plastic material the lower ends of the 55

2

wires 12 and 13 may be molded or inserted in them.

Extending from one set of parallel wire portions to the other set of parallel wire portions and between the wires of the respective sets, is a spool like element 15 having internal tapered faces 16 adapted to act in cam like fashion upon the respective wires when the upper ends 14 are brought together to cause the inward and clamping movement or engagement of the parallel retaining elements 10 and 11. As the upper ends 14 of the wire portions are brought together the wires are slid down over the inclined or tapered faces 16 of the spool like element 15. The wire sets 12 and 13 are accordingly brought together. When the upper ends 14 are released, the wire sets will expand and the retaining elements will be released from the trousers or skirt. The ends 14 are brought together by a pivoted hook 18 as the same is pivoted from its full lined position as shown in Fig. 3 to the upright or dotted line position. The hook 18 has a pivot connection as indicated at 19 with one of the ends 14. In this manner the hook is retained upon the wire portion. The hook further has a straight portion 21 which extends between the ends 14 to connect them together. Extending upwardly from the horizontal portion 21 is a camming portion 22 adapted to cause the opposite ends 14 to be brought toward the other or the one end 14 as the hook 18 is brought from the position shown in full in Fig. 3 to the dotted line position as indicated at 18'. After the opposite end 14 has been so cammed it will be retained on the horizontal portion 21 by a bend 23 between the horizontal portion 21 and the camming portion 22. The entire hook 18 is formed of a flat narrow strap.

Referring now particularly to Figs. 4 and 5, 40 there is shown a modified form of the invention. A hook 24, also formed of straps, is provided with a portion adapted to be connected to ends of wires 12', Fig. 5, to hold them together. This attaching portion is indicated at 25 and has wing portions 26 which are folded respectively around the upper ends of the wires 12' to be retained against slippage therefrom. Extending upwardly from the attaching portion 25 is a gooseneck 27 which extends forwardly as indicated at 28 to receive an end 14' on wires 13'. The portion 28 receives the transverse end 14' when the hook 24 is pivoted rearwardly upon the gooseneck 27 and the end 14' is retained on the portion 28 by a stop portion 29. When the hook 24 is released the end 14' will be retained as shown in Fig. 4 in a

pocket portion 31 of the hook 24 disposed above the stop portion 29. It will be apparent that by the arrangement shown in Figs. 4 and 5 the same closing movement of the wires is effected as in Figs. 1 and 2 and that the wires will be brought down upon the inclined faces 16 of the spool like element 15. In this latter form of the invention the hook 24 will always be held upright and in a position so that it can be used to suspend the hanger on a hook even though the hook portion has not been moved to the locked position as shown in dotted lines 24'.

While various changes may be made in the detail construction of the invention, it shall be understood that such changes shall be within the spirit and scope of the present invention as defined by the appended claims.

I claim:

1. A hanger for trousers or skirts comprising parallel retainer elements between which the trousers or skirt are extended, wire portions extending upwardly from the elements, two of such wire portions extending up from each of the elements and such portions being spaced apart, a spool like element extending from one set of wire portions to the other set and between the wire portions of each set, said spool like element having inclined portions over which the wire portions will slide as the upper ends of the wire portions are brought close together whereby to cause a camming action upon the wire portions to bring their lower ends together and the parallel retainer elements to place the same in clamping engagement with the trousers or skirt, and means for bringing the upper ends of the wire portions together and locking them in their brought together position.

2. A hanger as defined in claim 1, and a hook formation on said bringing together and locking means whereby the hanger with the trousers or skirt attached can be suspended from a fixed support.

3. A hanger as defined in claim 1, and said bringing together and locking means comprising a strip of material, said strip being pivotally anchored at one end to the wire portions of one set, said strip further having a camming edge adapted to engage with the end of the wire portions of the other set to cause the movement of the ends of this other set towards the ends of the one set, said strip having a recess in which the ends of the other set will fall into after the camming action has been effected upon the same and the strip has been pivoted to an upright position whereby to retain the ends of the sets of wire

portions in locked or compressed positions, and said strip having a hook formation on the same by which the hanger may be suspended from a fixed support.

4. A hanger as defined in claim 1, and said bringing together and locking means comprising a strip of material, said strip being pivotally anchored at one end to the wire portions of one set, said strip further having a camming edge adapted to engage with the end of the wire portions of the other set to cause the movement of the ends of the one set, said strip having a recess in which the ends of the other set will fall into after the camming action has been effected upon the same and the strip has been pivoted to an upright position whereby to retain the ends of the sets of wire portions in locked or compressed positions, and said strip having a hook formation on the same by which the hanger may be suspended from a fixed support, and said strip further having a recess for receiving the ends of one set of wire portions upon the wire portions being released at their upper ends whereby to maintain the strip in an upright position so that the hook formation can be used for suspending the hanger even though the strip has been moved to a position to release the upper ends of the wire portions.

5. A hanger as defined in claim 1, and said bringing together and locking means comprising a strip having an attaching portion for securing the strip to one set of wire portions, said attaching portion having laterally extending projections surrounding the ends of the wire portions in clamping engagement therewith, a gooseneck formation extending upwardly from the attaching portion, said gooseneck formation permitting the flexing of the strip, a recess for receiving the ends of the wire portions of the other set when the strip has been pivoted to bring the upper ends of the sets together and a hook formation on the strip serving as a handle by which the strip can be pivoted.
